UNITED STATES PATENT OFFICE.

JOHN A. ARENZ, OF CHICAGO, ILLINOIS, ASSIGNOR TO INTERNATIONAL SCREW COMPANY, OF WILMINGTON, DELAWARE, A CORPORATION OF DELAWARE.

DOUBLE-THREADED SCREW.

Application filed March 2, 1925. Serial No. 12,547.

My invention relates to screws having particular reference to a wood screw of the type used by carpenters, tradesmen and the like, and which is adapted to be turned into 5 position by means of a screw driver or the like.

The primary object of my invention is the provision of a screw having a tapered body portion with a double thread upon the body 10 portion of the screw, the said double thread terminating in a single penetrating point so that the screw will enter and separate the fibers of the wood into which the screw is driven rather than cut the fibers from the 15 wood as is common with screws of this type heretofore manufactured.

I am aware that screws of the same general type as my improvements have been used heretofore, but these screws have a pair of 20 incising blades at the end of the screw, each thread terminating in an incising blade and which cut the fibers of the wood as the screw is driven into the wood, and which cut out the fibers of the wood at least to the diameter 25 of the two incising blades and thereafter the fibers are spread somewhat and engaged by the threads on the side of the screw. The common ordinary type of commercial screw has a single thread which terminates in a 30 point, but this point is not an incising one and in driving this screw into wood a gimlet hole must be made, particularly if the wood is hard, before the screw can be driven into the wood at all.

Another object of my invention is the provision of a double threaded screw, having the threads fashioned into a single penetrating point and which has the thread formed thereon having a longer angle at the upper 35 side of the thread than at the under side thereby enabling the screw to force its way 40 into wood easier than the ordinary screw and with less force needed to drive it into position.

Another and further object of my invention is the provision of a screw which can be easily and cheaply manufactured and which has an incising or chiseled point thereon which enables it to be driven into the wood 45 in a straight line without the danger of breaking the point which sometimes occurs

with a double point screw of the type above described and resulting in the screw traveling at an angle into the wood, which also occurs when the two points of the double threaded 55 screw are not exactly even.

These and other objects of my invention are more fully described and better understood by referring to the accompanying sheet 60 of drawings in which

Figure 1 is a side elevational view of the screw embodying my invention, and

Figure 2 is a diagrammatic view, showing the outlines of the threads in an enlarged 65 form converging to cutting edges tapering to a point.

Figure 3 is a side elevational view of the screw, shown at right angles to the illustration in Figure 1.

Referring now specifically to the drawings 70 and in which like reference characters refer to like parts throughout, a screw 10 is shown having a head 11 secured thereto with transversely extending slot 12 therein so that the head may be engaged by a screw driver or 75 the like. The screw 10 is formed with the stem 13 having a tapered portion 14 terminating in a central penetrating point 17, and the double threads 15 and 16, slightly undercut, and extending from said stem into and 80 along the tapered portion 14 thereof and finishing on either side of the point 17 and merging into the cutters 18 and 19, which converge to said point across the grooves or 85 channels 20 and 21 of the threads respectively.

The operation of the device is exceedingly simple there being no necessity for making a gimlet hole or an incision into the wood as there is with either a single thread screw or 90 a double thread screw with two points, unless the wood is exceedingly hard, and for this reason the screw also is much easier secured in place than screws of this type which have heretofore been manufactured, and hold in 95 position very much better than an ordinary screw or the double threaded two point screw.

Though a preferred embodiment of the present invention has been described in 100 detail, it will be clear that many modifications will occur to those skilled in the art.

It is intended to cover all such modifications that fall within the scope of the appended claim.

What is claimed is:

- 5 A screw comprising a stem and tapered point having a plurality of threads spirally extending to the extreme tip of the tapered portion, the ends of said spirals being

merged to form a sharp point and forming oppositely positioned cutting edges extending from said point to initially open the work to the path of the screw in penetrating operations.

Signed at Chicago, Illinois, this 21st day of February, 1925.

JOHN A. ARENZ.
